DESIGN FOR ELASTIC FABRIC

Stanley D. Kops, New York, N. Y., assignor to
Kops Brothers, Inc., New York, N. Y., a corpora-
tion of New York

Application July 17, 1933, Serial No. 48,743

Term of patent 14 years

To all whom it may concern:

Be it known that I, STANLEY D. KOPS, a citizen of the United States, residing at New York, in the county and State of New York, have invented a new, original, and ornamental Design for Elastic Fabric, of which the following is a specification, reference being had to the accompanying drawing, forming a part hereof.

The figure illustrates a section of elastic fabric embodying the new design, the small, irregular, square formations being depressed or set-in with relation to the rest of the fabric.

I claim:

The ornamental design for elastic fabric, as shown and described.

STANLEY D. KOPS.
